[57] **CLAIM**

The ornamental design for multiple dosage packets severable from one another along perforated lines of weakness, as shown and described.

DESCRIPTION

FIG. 1 is a front elevational view of a multiple dosage packets severable from one another along perforated lines of weakness showing my new design;

FIG. 2 is a bottom plan view thereof;

FIG. 3 is a rear elevational view thereof;

FIG. 4 is a left side elevational view thereof, the right side being identical; and,

FIG. 5 is a top plan view thereof.

The broken lines shown on FIGS. 1 and 3 represent tear lines.
